UNITED STATES PATENT OFFICE.

MAX ROCKSTROH, OF KLEIN-SEDLITZ, NEAR PIRNA, GERMANY.

PLATEN PRINTING-PRESS.

1,118,055.

Specification of Letters Patent.

Patented Nov. 24, 1914.

Application filed June 10, 1913. Serial No. 772,846.

To all whom it may concern:

Be it known that I, MAX ROCKSTROH, a citizen of the German Empire, and residing at Klein-Sedlitz, near Pirna, Saxony, 5 Germany, have invented certain new and useful Improvements in Platen Printing-Presses, of which the following is a specification.

My invention relates to a pressure regulator having lever transmission for platen printing presses, wherein the handle which is grasped for disengaging the platen is so arranged that it can be moved, when removing the pressure, only in a direction opposite to the direction of motion of the platen on its pressure stroke, so that disengagement can be very conveniently effected by merely grasping the handle without power needing to be exerted, and the stoppage of the motion can be thereby brought about. The members on which the levers for removing the pressure are fulcrumed are firmly clamped on the pressure regulating pins, in order that they may be accurately adjusted in 25 height.

Platen presses having pressure regulators comprising lever transmission are already known, in which the pressure is removed by moving a handle arranged at the ends of the levers. In these devices, however, the members on which the levers are fulcrumed are rigidly connected with the pressure regulator pins. Hence it follows that the pressure regulator pin needs to be fitted into the graduated indicator with extreme precision, for otherwise either too much or too little clearance would exist for the pressure regulator pins between the ways along which the ends of the levers move and the surfaces of 40 the guiding eyes. As compared with these known devices, my above-described arrangement wherein the said members on which the levers are fulcrumed are arranged independent of the pressure regulator pins and adjustable on the same, has the advantages resulting from exact adjustment and fitting. A further improvement is the arrangement and form of the levers themselves. The fulcrums of the levers and the 45 form of the cam faces on the same are such that the handle can be moved

only in the direction opposite to that of the motion of the pressure stroke of the platen. It is consequently possible by simply grasping the handle to arrest the motion of the 55 same and, as the platen moves still farther forward, to snap out the pressure regulator pins. Consequently the pressure is removed without trouble. In the known devices such removal of the pressure is not nearly so simple; for in these cases a special movement of the hand, a so-called "knack," is always first requisite, which must be given in the same direction as that in which the platen moves during its pressure stroke. 60

One illustrative embodiment of my invention is represented by way of example in the accompanying drawings, wherein:—

Figures 1 and 2 show the pressure regulator in side and end elevation, respectively; 70 Fig. 3 is a plan, enlarged, showing one half of the pressure regulator; Figs. 4 and 5 are elevation and plan, respectively, showing the members for receiving the handle; Figs. 6 and 7 are elevation and plan, respectively, 75 showing the lever for actuating the pressure regulator, and the attachment shackle for the lever.

Referring to the drawings, the member *b* having the form of a shackle is slid onto the upper end of the known pin *a* of the pressure regulator, and is immovably fastened to said pin by means of a screw *b'*. The height of the shackle-like member *b* is adjusted and regulated by slackening the screw and pushing the member up or down. 80

Mounted in the member *b* is a pin *c*, whereon rocks the releasing lever *d* having an eye *f* which is pushed over the pin *c*. Rigidly connected with the releasing lever *d* or integral with the same is a shackle *g* 90 which receives the handle *e*, the latter being immovably fastened therein by tightening the screw *e'*. In the position of the lever *d* in which the entire device is disengaged, the curve of the cam runs toward the rear side of the machine from the horizontal into the vertical. The curve of the cam *h* is therefore in its rear portion eccentric with the pin *c*. I thus obtain that when the handle 95 bar *e* is operated when the platen advances, this bar needs to be only grasped in order 100

to disengage the pressure regulator *a* without difficulty and, consequently, to remove the pressure.

I claim:—

- 5 In a platen printing press, the combination of a pressure regulator comprising a pin, a shackle adjustable thereon, a pivot mounted on the shackle, a disconnecting lever fulcrumed on the pivot, and a handle-
10 bar carried by the lever, the handle-bar

being movable, when removing the pressure, in a direction opposite to the direction of motion of the platen during its pressure stroke.

In testimony whereof, I affix my signature 15
in the presence of two witnesses.

MAX ROCKSTROH.
